UNITED STATES PATENT OFFICE

NORMAN CLEMENCE, OF NEW YORK, N. Y., ASSIGNOR TO SCOTT PAPER COMPANY, OF CHESTER, PENNSYLVANIA, A CORPORATION

DESIGN FOR A TOWEL OR SIMILAR ARTICLE

Application filed November 10, 1931. Serial No. 41,684. Term of patent 3½ years.

To all whom it may concern:

Be it known that I, NORMAN CLEMENCE, a subject of the Kingdom of Great Britain, now residing at New York city, county of New York, and State of New York, in the United States of America, have invented a new, original, and ornamental Design for a Towel or Similar Article, of which the following is a specification, reference being had to the accompanying drawing, forming a part thereof.

The drawing shows a plan view of a towel or similar article embodying my new design. The detailed illustration showing the border design also appears on the opposite end of the towel or similar article, and the design of the surface of the towel or similar article shown in detail extends between the opposite borders.

I claim:

The ornamental design for a towel or similar article, as shown and described.

NORMAN CLEMENCE.
